UNITED STATES PATENT OFFICE.

CHARLES F. WILLIAMS, OF PERU, INDIANA.

HEAD-REST.

SPECIFICATION forming part of Letters Patent No. 568,710, dated September 29, 1896.

Application filed April 13, 1896. Serial No. 587,329. (No model.)

To all whom it may concern:

Be it known that I, CHARLES F. WILLIAMS, a citizen of the United States, residing at Peru, in the county of Miami and State of Indiana, have invented a new and useful Head-Rest, of which the following is a specification.

My invention relates to an improved head-rest for barbers' chairs; and it has for its object the production of a head-rest the cushion of which may be quickly and conveniently removed from its normal position to a position entirely out of the way of the barber, thus adapting the chair for use in hair-cutting without delay.

15 The invention will first be described in connection with the accompanying drawings and then pointed out in the claim.

Figure 1 of the drawings is a perspective view of my improved head-rest, showing it in the normal position and attached to the ordinary ratchet-bar, a short length of the latter only being shown. Fig. 2 is a perspective view of the same, the cushion being thrown back into the inoperative or lowered position. Fig. 25 3 is a side elevation, partly in section, of the head-rest in place on a chair, the cushion being shown in the normal position in full lines and in the lowered position in dotted lines.

30 Referring to the drawings, A represents an ordinary barber's chair, and B a ratchet-bar secured thereto, this bar being adapted for vertical movement with relation to the chair, as in the ordinary construction.

35 C is a cap, preferably of metal, adapted to snugly fit the upper end of the ratchet-bar B and be secured thereto by a bolt c. The upper surface D of this cap is plain and preferably slopes in a forward and downward direction, and from the rear end of this cap project two parallel and slightly-curved arms d, for a purpose hereinafter described.

E represents the cushion-plate, to which an ordinary cushion F is adapted to be secured. 45 To the forward end of plate E is hinged a plate G, provided at its rear end with two parallel arms g, which are pivotally connected to the arms d on cap C, as shown.

H represents a locking-spring, being simply 50 a strip of spring metal preferably bent in the shape shown, secured at one end to the cushion-plate E, and having at or near its other end a hole h, which, when the cushion

is in the normal position, is adapted to take over a stud e, projecting from the rear side 55 of cap C.

The operation of my improved head-rest is as follows: Assuming the cushion to be in the normal position, as shown in Fig. 1, the plate G will rest on the cap C and support the 60 cushion-plate E, the inclined surface D of cap C permitting the cushion to occupy the proper position to receive the head of a person sitting in the chair. It will be noticed that in the normal position of the cushion the stud e on 65 cap C has entered the hole h in spring H, thus securely holding the cushion against accidental movement. Now if it is desired to place the cushion in the lowered position the spring H is sprung off the stud e and the 70 cushion is thrown back, when the pivotal connection between the arms d and g and between the plate G and the cushion-plate E will cause the cushion to assume the position shown in full lines in Fig. 2 and in dotted 75 lines in Fig. 3, the free end of the spring H contacting with the ratchet-bar B and maintaining the cushion a slight distance therefrom in a position to be easily grasped when it is desired to return it to the normal position. 80

Having thus described my invention, what I claim as new, and desire to secure by Letters Patent, is—

In a head-rest, the combination, with a 85 chair and a vertically-movable ratchet-bar attached thereto, of a cap adapted to receive the upper end of the ratchet-bar and having two rearwardly-projecting parallel arms, a cushion-plate carrying a cushion, a plate 90 hinged at one end to the cushion-plate and having at the other end two parallel arms pivotally connected to the arms projecting from the cap, and a spring adapted to lock the cushion-plate in the normal position, and 95 to bear against the ratchet-bar when the cushion-plate is in the lowered position, substantially as described and for the purposes stated.

In testimony that I claim the foregoing as 100 my own I have hereto affixed my signature in presence of two witnesses.

CHARLES F. WILLIAMS.
